UNITED STATES PATENT OFFICE

134,312

DESIGN FOR A CANDLESTICK ADAPTER OR SIMILAR ARTICLE

Carl J. Uhrmann, Bellaire, Ohio, assignor to Imperial Glass Corporation, Bellaire, Ohio, a corporation of Ohio

Application June 24, 1942, Serial No. 107,324

Term of patent 14 years

To all whom it may concern:

Be it known that I, Carl J. Uhrmann, a citizen of the United States of America and resident of Bellaire, county of Belmont, and State of Ohio, have invented a new, original, and ornamental Design for a Candlestick Adapter or Similar Article, of which the following is a specification, reference being had to the accompanying drawings, forming part thereof, in which—

I claim—

The ornamental design for a candlestick adapter or similar article, substantially as shown.

CARL J. UHRMANN.
